UNITED STATES PATENT OFFICE.

ALBERT P. GATHRIGHT AND ANTHONY W. POTTS, OF COOPER, GEORGIA.

MACHINE FOR SHARPENING GIN-SAWS.

SPECIFICATION forming part of Letters Patent No. 259,125, dated June 6, 1882.

Application filed March 3, 1882. (No model.)

To all whom it may concern:

Be it known that we, A. P. GATHRIGHT and A. W. POTTS, of Cooper, in the county of Jackson and State of Georgia, have invented 5 certain new and useful Improvements in Machines for Sharpening Gin-Saws; and we do hereby declare that the following is a full, clear, and exact description of the invention, which will enable others skilled in the art to 10 which it appertains to make and use the same, reference being had to the accompanying drawings, which form a part of this specification.

Figure 1 is a perspective view, Fig. 2 is a side view, and Fig. 3 is a longitudinal vertical 15 sectional view, of our improved gin-saw-sharpening machine.

Corresponding parts in the several figures are denoted by like letters of reference.

This invention relates to machines for sharpening gin-saws; and it consists in certain improvements in the construction of the same, which will be hereinafter fully described, and particularly pointed out in the claims.

In the drawings hereto annexed, A represents the frame of the machine, which is provided near its rear end with bearings for the transverse main shaft B. The latter has a gear-wheel, C, engaging a pinion, C', upon the rear end of the longitudinal driving-shaft D, to 25 which motion may thus be imparted.

E is a rock-shaft mounted transversely in the frame A, and carrying a rearward-extending lever, F, which is operated by a cam, G, upon the main shaft B. Rock-shaft E also 35 has an opening or slot, H, in which a lever, I, is vertically adjustable by a set-screw, J. The lever I bears against and operates an arm, K, projecting downwardly from a rock-shaft, L, mounted in frame A in front of and above the 40 rock-shaft E. Arm K carries a forward-extending pawl, M, which projects slightly in front of the machine, so as to engage the teeth of the saw, which has been suitably mounted for sharpening, and turn the said saw forward 45 the space of one tooth at each stroke or operation. The stroke may be regulated to suit saws with teeth of various sizes by properly adjusting the lever I.

Mounted in suitable bearings upon the top 50 of frame A is a longitudinally-sliding shaft, N, having near its front end a cross-head, O.

P is a vertical shaft, journaled in said cross-head and carrying at its lower end a pinion, Q, engaging and operated by a worm, R, upon the front end of the driving-shaft D. At its upper end the shaft P carries a gear-wheel, S, engaging a pinion, T, upon the upper end of a short vertical shaft, U, which is mounted in the front end of slide N, and which carries at its lower end the circular file W. The slide N 55 is operated by an arm, V, extending upward from the rock-shaft L and engaging a stud, X, upon the under side of said slide. A spring, Y, is suitably arranged to force the said slide automatically in a forward direction. 60

The machine may be operated by hand by means of a crank, Z, upon one end of the main shaft B, or by any suitable motive power applied in any well-known manner.

In operation the saw which is to be sharpened is to be suitably mounted in front of the machine, facing the file. When the main shaft is revolved the cam G strikes and operates the lever F, thus oscillating the rock-shaft E, the lever I of which operates arm K and pawl M, 70 which latter advances the saw the space of one tooth. By the same operation the arm V of rock-shaft L forces the slide N, with its attachments, in a rearward direction, thus moving the file back from the saw. The moment 75 the lever F is released from the pressure of cam G the slide N advances, and the file, which is rotated by the driving-shaft D and intermediate mechanism, operates upon the saw. While the slide N is moved rearward the pinion 80 Q of the shaft P would be revolved in a reverse direction by its teeth engaging the spirals of the worm R, provided the latter remained stationary while the rearward movement of slide N took place; but as the said worm continues 85 to revolve, engaging the pinion Q, it compensates for the reverse movement of said pinion, and the latter, together with the parts operated by it, remains practically at a standstill while the slide N moves back. 90

Having thus described our invention, we claim and desire to secure by Letters Patent of the United States—

1. The combination, in a machine for sharpening gin-saws, of the main shaft B, having 100 cam G, rock-shaft E, having lever F and vertically-adjustable arm I, and the rock-shaft L,

having arm K, provided with a forward-extending pawl, M, substantially as set forth.

2. As an improvement in machines for sharpening gin-saws, the combination of the main shaft B, having cam G, rock-shaft E, having lever F and vertically-adjustable arm I, rock-shaft L, having arm K, provided with pawl M and arm V, the driving-shaft D, having pinion C' and worm R, the slide N, having stud X, shafts P U, gear-wheel S, pinions T Q, and file

W, and the spring Y, all arranged and operating substantially as set forth.

In testimony that we claim the foregoing as our own we have hereto affixed our signatures in presence of two witnesses.

ALBERT P. GATHRIGHT.
ANTHONY W. POTTS.
